Attorney

UNITED STATES PATENT OFFICE.

WILLIAM H. FRAMPTON, OF CHARLESTON, SOUTH CAROLINA.

NONREMOVABLE CAP FOR CONTAINERS.

Application filed April 28, 1928. Serial No. 273,726.

My invention relates to a non-removable cap for collapsible metal tubes, which tubes are adapted to contain such articles as cosmetics, drugs, food products, paint products, 55 convenient and compressed products such as various gases which are shipped under compression and in fact any product having a viscosity which will permit the same to be removed from a collapsible metal tube or a non-collapsible metal tube, as I desire it to be understood that my invention may be applied to a rigid tube as well as to a collapsible tube.

A further object of my invention is to provide a non-removable cap for container tubes 15 which have their exit portion on the side thereof and the cap being adapted to cover said exit portion or to be removed from over said exit portion.

Some of the objects of my invention having 20 been stated, other objects will appear as the description proceeds, when taken in connection with the accompanying drawings in which,—

Figure 1 is a side elevation of the upward 25 portion of a tube showing my cap in closed position;

Figure 2 is a cross-sectional view of Figure 1;

Figure 3 is a view similar to Figure 1 with 30 the cap in raised position;

Figure 4 is a cross sectional view of a modified form of my invention.

Referring more particularly to the drawings, the numeral 10 indicates a tubular container having the neck portion 11, which neck portion has the restricted portion 12 and the upper end of this neck portion 13 is closed and has the threads 14 thereon. In the portion 11 there is the hole 15 through which the 35 contents of the tube are adapted to be discharged. Fitting over this neck portion is the cap member 16 which is closed at its upper end and has the crimped ring 17 there-around to fit against the restricted portion 12, and the upper portion 18 has interior threads for engagement with the threads 14 on the portion 13 of the neck.

In Figures 1 and 2 this cap is shown in closed position while in Figure 3 it is shown 40 in raised position, and when in raised position the threads 14 do not engage the interior

threads of the portion 18 and this allows the cap to slide upwardly on the portion 12 until the projection 17 fits against the portion 13.

In Figure 4 I have shown a slightly modified form of my invention which has the tube 10 with the straight neck portion 21 with the enlarged upper portion 22 and the cap portion 24 has the crimp 25 therein which fits against the restricted portion 21 and prevents 55 the cap 24 from being removed. This neck portion has the exit hole 23 through which the contained substance is adapted to be forced and has the raised threads 27 disposed around the portion of the neck in which the 60 hole 23 appears and the interior threads 26 in the cap 24 engage the threads 27 to hold the cap in closed position.

It is thus seen that I have provided a tube 65 having a non-removable cap which is rigid 70 and practically indestructible and which can be adapted for use not only on collapsible tubes but also on rigid tubes.

In the drawings and specification I have 75 set forth a preferred embodiment of my invention, and although specific terms are employed, they are used in a generic and descriptive sense only, and not for purposes of limitation, the scope of the invention being set forth in the appended claim.

I claim:

In a collapsible metal tube adapted to serve as a container for fluids and the like, an extended neck portion, an opening in the base portion of the neck portion, a restricted portion to the said neck portion, an enlarged portion at the end of the neck portion, threads on said enlarged portion, a cap adapted to fit over the neck portion, interior threads in the cap portion adapted to engage 85 the threads on the end of the neck portion, a restricted portion intermediate the ends of said cap, said restricted portion being adapted to fit into the restricted portion of the neck portion, the lower end of the cap being adapted to fit over the opening to close the same when driven home, and the restricted portions permitting the cap to slide from over the opening when the threads in the cap are released from the threads on the neck.

In testimony whereof I affix my signature.

WILLIAM H. FRAMPTON.
